DESIGN FOR A CLOSET BOWL

Hugh R. Van Sciver, Trenton, N. J., assignor to Crane Co., Chicago, Ill., a corporation of Illinois

Application September 8, 1939, Serial No. 87,095

Term of patent 14 years

To all whom it may concern:

Be it known that I, Hugh R. Van Sciver, a citizen of the United States, residing at 309 N. Clinton Avenue, in the county of Mercer, city of Trenton, and State of New Jersey, have invented a new, original, and ornamental Design for a Closet Bowl, of which the following is a specification, reference being had to the accompanying drawing, forming part thereof.

The drawing represents a perspective view of a closet bowl embodying my design.

The side not shown is identical to the side shown.

I claim:

The ornamental design for a closet bowl, substantially as shown and described.

HUGH R. VAN SCIVER.
